UNITED STATES PATENT OFFICE

133,900

DESIGN FOR A MEAT BLOCK

Samuel Jackson Brown, West Point, Ky.

Application July 27, 1942, Serial No. 107,717

Term of patent 7 years

To all whom it may concern:

Be it known that I, Samuel Jackson Brown, a citizen of the United States, residing at West Point, in the county of Hardin and State of Kentucky, have invented a new, original, and ornamental Design for a Meat Block, of which the following is a specification, reference being had to the accompanying drawing, forming part thereof.

In the drawing:

I claim:

The ornamental design for a meat block, as shown.

SAMUEL JACKSON BROWN.
